United States Patent Office

Des. 222,531
Patented Nov. 2, 1971

222,531

RETAIL FOOD MARKET

Howard Cooper, Suite 7707, John Hancock Center,
Chicago, Ill. 60611

Filed Mar. 19, 1970, Ser. No. 21,972

Term of patent 14 years

Int. Cl. D25—03
U.S. Cl. D13—1

FIG. 1 is a perspective view of a retail food market embodying my design; and

FIG. 2 is a top plan view thereof.

I claim:

The ornamental design for a retail food market, substantially as shown.
